ARTHUR V. DICKEY, OF SEATTLE, WASHINGTON, ASSIGNOR OF ONE-HALF TO WM. M. SHEFFIELD, OF SEATTLE, WASHINGTON.

REPEATING AIR-RIFLE.

1,026,303.

Specification of Letters Patent.

Patented May 14, 1912.

Application filed October 26, 1911. Serial No. 657,009.

To all whom it may concern:

Be it known that I, ARTHUR V. DICKEY, a citizen of the United States, residing at Seattle, in the county of King and State of Washington, have invented certain new and useful Improvements in, Repeating Air-Rifles, of which the following is a specification.

The object of this invention is the provision of a repeating air-gun of simple and inexpensive construction and one which may be employed instead of the ordinary fire-arm for shooting small game, target practice, etc.

15 The invention consists in the novel construction and combination of parts, as will be hereinafter described and claimed.

In the drawings, Figure 1 is a longitudinal vertical section of an air gun embodying my improvements. Fig. 2 is a side elevation thereof. Fig. 3 is a horizontal sectional view taken on plane 3—3 of Fig. 1. Fig. 4 is a view similar to Fig. 3 but showing the breech-block and the operating mechanism therefor in different positions. Fig. 5 is a perspective view of the breech-block actuator, and Fig. 6 is a like view of the breech-block.

30 The reference numeral 10 designates a frame to which the gun barrel 11 and the stock 12 are rigidly secured. The rear end of the barrel is socketed in a member 13 which is chambered as at 13' to receive the breech block 14. Communication is had by passage 15, arranged to be in alinement with the barrel bore, between the chamber 13' and an air receiver 16 which in turn is communicatively connected by a duct 17 with an air reservoir 18. The latter is desirably disposed within the gun-stock and may advantageously constitute a part of the stock structure, as illustrated in Fig. 1. At its inlet end, the passage 15 is provided with a seat 15' for a valve 19 which is yieldingly held in closed position by a spring 19'.

20 represents a pump cylinder having communicative connection from its rear end with said reservoir through a tube 21. A spring pressed check, or non-return, valve 22 is utilized to prevent any reverse flow of air from the reservoir. A vent hole 23 is provided in the pump cylinder in proximity to the valve 22 and is normally closed by a screw plug 24 engaging in screw threads formed in the hole. Said pump cylinder is

arranged to have its axis parallel, or nearly so, to the gun-barrel. The pump plunger 25 is secured to an end of a piston rod 26 whose other end is connected by a link 27 with a lever 28 at about the midlength of 60 the latter. This lever is connected from its forward end by a hinge 29 to the underside of the gun frame 10, against which it is laid when unemployed. The lever serves as a pump handle to operate the plunger 25, the 65 piston-rod 26 thereof being maintained in axial relation to the pump cylinder by an attached block 30 which is slidably mounted on a guide bar 30'.

To one side of the gun barrel 11 is a detachable tube 31 which serves as a magazine for the projectiles. Such magazine may be secured by having its rear end introduced into a socket 32 provided in the member 13 while its forward end is held firmly against 70 the gun-frame by means of a button catch 33. Within the magazine is a cylindrical plug 34 which is yieldingly pressed toward the open rear end of the tube by means of a helical spring 35 and whereby the projectiles, such as P, are pressed rearwardly to be fed to the breech-block 14 as required. The plug 34 is provided with a tongue 34' which projects through a longitudinal slot 31' in the magazine wall. 80

At the forward end of the slot is a notch 31' whereinto the tongue 34' is engaged to hold the spring 35 while the projectiles are being placed in the magazine. After the magazine is charged and restored to the gun 90 the tongue 34' is withdrawn from the notch 31' whereby the spring 35 is rendered operative to feed the projectiles. The aforementioned breech-block 14, as best shown in Figs. 4 and 6, consists of a plug having a 95 cylindrical end 14', a tapering middle portion 14² and is of a polygonal shape at the other end, as at 14³.

The chamber 13' for the reception of the breech block is shaped to accommodate the same and the office of the chamber part 13² with which the polygonal end of the block engages is to prevent the latter from turning. In the tapering portion of said block is a conical shaped aperture 37, or pocket, 100 as it will be hereinafter designated, which extends diametrically through the block. This pocket is positioned so as to be presented to the magazine to receive a projectile when the block is in one position (Fig. 110

4) and also when the block has been shifted into the position in which it is represented in Fig. 3 the pocket will be brought in alignment with the barrel bore and the air supply passage 15. Said block is manipulated to effect its inward and outward movements through the medium of an actuator 38 which is connected to the gun frame for longitudinal reciprocatory movements, as by headed 70
10 guide pins 39 and a strap 39' hooked over the upper edge of the actuator. Said actuator is provided with a flange or plate 38' having a cam slot 38² whereto protrudes a pin 40 rigid with the breech-block. The 15 cam slot is adapted to afford an outward movement to the breech block when the actuator is shoved forward and when drawn toward the rear the cam-slot influences the pin 40 to effect the inward movement of the 20 breech block for bringing the same into firing position.

41 denotes a plate of resilient material secured to the gun-frame and between which and the plate 41 the rear end of the actuator 25 is engaged to prevent any accidental dis- placement of the actuator or of the associated breech block when the latter occupies the position it will assume when the gun is ready for firing.

30 42 is a handle extending from the actuator for operating the same.

Below the gun barrel (Fig. 1) is a tube 43 containing the main spring 44 arranged to urge a hammer block 45 rearwardly to 35 encounter a firing pin 46 which, in turn, is driven by the spring impelled block 45 to unseat the valve 19, as will presently be explained. The hammer-block is provided with a stud 45' which extends through a 40 slot provided in the tube 43 and also through a slot 47 (Fig. 2) provided in the gun frame.

When the actuator is thrust forward it 45 engages the stud 45 and thus effects the forward travel of the hammer block to accomplish the compression of the main spring 44. To arrest the block 45 against accompanying the actuator when being returned to its normal position, I provide a bell crank 50 lever 48 having an arm 48' which is urged upwardly by a spring 49 to obstruct the block, as will be understood from an inspection of Fig. 1. Said lever is fulcrumed to the frame by a pivotal pin 50 and has a 55 depending arm 48² which is connected by a pull rod 51 with a trigger 52 fulcrumed to a pivotal pin 53.

As illustrated in Fig. 4, a leaf spring 54 is desirably provided to protrude into the 60 barrel bore to obviate a projectile dropping out of the breech block pocket in the event of the muzzle end of the gun being directed downwardly. Another feature of the gun, and one of considerable importance where 65 accurate shooting of the arm is desirable, is

the rifling of the barrel bore. Such rifling consists of helical ridges 55 provided in the periphery of the bore and extending from the muzzle end to within a distance of the breech. By such devices the projectile at- 70
75 tains considerable momentum before encountering the rifling and in consequence the velocity of the projectile is not appreciably impeded by the referred to ridges.

The operation of the invention may be 75 explained as follows: The reservoir is supplied with air under compression by operating the pump through the instrumentality of the lever 28 and the link 27 which, in effect, serve as toggle elements (see broken 80

lines 28^a and 27^a, Fig. 1, of the respective parts) to afford a relatively great pressure to the air during the termination of each pumping stroke of the pump plunger 25.

The magazine 31 is charged with the projectiles by removing the same from the gun frame and with the plug 34 held at the end of its forward travel through the agency of the tongue 34' thereof being engaged in the 85
90 notch 31². The magazine thus loaded is re-

turned to the gun frame and secured to same by the button fastener 33. The tongue 34' is then removed from said notch to release the spring 35 for operation. To prepare the 95
100 gun for firing, the actuator 38 is thrust for-

ward by the operator's hand grasping the handle 42 with the result that the hammer block 45 is pushed forward by the actuator through the medium of the stud 45' to com-

press the main spring 44. At or near the end of the forward travel of the hammer block it is engaged by the arm of the bell- 105
110 crank lever 48 which is accordingly influ-

enced by the spring 49. In such forward movement of the actuator, the cam slot 38² thereof causes the pin 40 to give axial motion to the breech block 14 to move the same from the position in which it is illustrated in Fig. 3 to that in which it is shown in Fig.

4 and thereby present the block-pocket 37 in line with the magazine. The spring 35 then asserts its power to shove one of the projectiles P into said pocket. The actuator is now retracted to cause the cam slot thereof to actuate through pin 40 the breech block 14 to return same to its former position (Fig. 3) with the block pocket in axial alignment with the barrel bore. To fire the gun, the trigger 52 is pulled resulting in the rod 51 affecting the bell-crank lever 48 to dis-

engage same from the hammer block 45, whereupon the main-spring 44 becomes oper- 115
120
125

ative to drive the hammer-block with con- siderable force against the firing pin 46 and the latter to transmit the power thus derived against the valve 19, opening the valve in

opposition to the spring 19 and the air pressure prevailing within the receiver 16. When this valve is opened a quantity of 130
135 compressed air is exhausted from the re-

ceiver and flowing through passage 15 to the rear of the projectile to eject the same from the gun. After the valve 19 has been unseated through the momentum of the hammer block transmitted by the firing pin, the spring 19' reacts to overcome the spring 44 sufficiently to replace the valve upon its seat to prevent further discharge of the air until another projectile is to be fired.

10. What I claim, is—

1. In an air-gun, a magazine for projectiles, a gun-barrel, a compressed air reservoir, communicative connections between said reservoir and the barrel, a valve for 15 said connections, trigger controlled normally inoperative devices for actuating said valve, means for conveying one projectile at a time from said magazine to said barrel, said means also serving to render said devices 20 operative, an air-pump cylinder, a connection between the cylinder and said reservoir, a non-return valve in the last named connection, a plunger for said cylinder, a pump handle hingedly connected to said gun 25 frame, and operative connection between the pump handle and said plunger.

2. In an air-gun, a magazine for projectiles, a gun barrel, an air reservoir connected

by an air-passage with the rear end of said barrel, a valve for said passage, trigger controlled normally inoperative devices for actuating said valve, and means for conveying one projectile at a time from said magazine to said barrel, said means also serving to render said devices operative.

3. An air-gun provided with a gun-frame, a reservoir for compressed air, a gun-barrel, a passage between the reservoir and the gun barrel, a valve for said passage, a breech-block, a receptacle for a projectile provided in said breech-block, an actuator movably connected to said gun-frame, a hammer-block for said valve, a spring for operating the hammer-block, and operative connection between the actuator and the hammer-block 45 and also between the actuator and said breech-block whereby the hammer-block and the breech-block are respectively actuated to cause the compression of said spring and to afford motion to the breech-block to present 50 the receptacle thereof successively to the magazine and to the gun-barrel.
